UNITED STATES PATENT OFFICE.

PAUL R. SAURER, OF NEW YORK, N. Y., ASSIGNOR TO THE PEELE COMPANY, OF NEW YORK, N. Y., A CORPORATION OF NEW YORK.

DUMBWAITER DOOR.

Application filed April 14, 1927. Serial No. 183,649.

My invention relates to dumbwaiter doors, and more particularly to those details of construction permitting the manufacture of a complete dumbwaiter door structure in the 5 factory, and facilitating the setting thereof during the construction of the wall of the shaft openings closed by such doors.

Heretofore in the production of fabricated dumbwaiter door structures, it has been the 10 usual practice to construct a framework of angle or flat bar metal stock, the uprights of which included therein the guide rail structures for the door panels, suitable anchoring devices to be imbedded in the 15 masonry, and reinforcing cross bars at the sill and lintel of the dumbwaiter opening. The panels themselves were made of an angle metal frame carrying special guide shoes co-operating with the vertical rails or 20 guides, and had the opening of the frame, closed by a sheet of metal riveted or otherwise secured to the angle metal frame. The dumbwaiter door itself had two panels having 25 flexible connections passing over sheaves supported by the uprights within the dumb- 30 waiter shaft, so that in opening the door the panels would move in opposite directions.

Dumbwaiter doors constructed as above, have been extensively used, and may be 35 cheaply produced. Owing to the construction of the main frame of the dumbwaiter door, however, the setting of the structure during the construction of the wall of the shaft required care in setting the frame and 40 in keeping it in position while setting the masonry about same, and the building up of the wall itself about this frame, offered considerable difficulties. Furthermore, the construction of such doors was such as to require 45 the installation of sills, lintels and jambs, and the use of trim about dumbwaiter shaft openings to give an attractive finish to the room. In fact, while such dumbwaiter doors may be economically produced and conveniently installed, nevertheless 50 there is considerable labor cost involved in their installation.

With the above conditions in mind, I have 55 provided a dumbwaiter door which may not only be fabricated in its entirety in the factory, but which may be quickly and accurately placed in position during the construction of the wall of the shaft, and when so positioned will serve as a form to assist

the mason in building up the shaft wall 55 about same. The dumbwaiter door structure has embodied therein as an integral part thereof, a fireproof trim, thus avoiding all subsequent finishing of the wall of the shaft about a door opening. 60

The dumbwaiter door structure in its entirety is light of weight, as compared with the older structures above referred to, since it may be made substantially throughout of 65 fairly light sheet metal stock, so flanged as to not only provide the desired framing to assist the mason in building up the wall, but to impart rigidity to the entire dumbwaiter structure. This employment of flanged 70 sheet metal parts extends not only to the opening form and its trim, but to the rail structures carried thereby, and the door panels having movement in said rail structures.

In connection with the formed sheet metal 75 panels, I provide special bearing shoes co-operating with the sheet metal guides which will reduce the bearing area between said panels and said guides, and thus ensure continued ease of movement of the doors.

The invention consists primarily in a 80 dumbwaiter door embodying therein a sheet metal form composed of a bottom, a top and parallel spaced side rails permanently connected and, defining the door opening in a shaft, said rails respectively forming the 85 sill, the lintel and the jambs of said opening, and having outwardly extending flanges so spaced as to receive the masonry of the shaft about the opening within said form, guides carried by flanges of the side rails of 90 and extending vertically beyond said top and said bottom rails respectively, sheet metal door panels slidably mounted in said guides, sheaves carried by said guides, and flexible connections extending from one of 95 said panels to the other, and passing about said sheaves; and in such other novel features of construction and combination of parts, as are hereinafter set forth and described, and more particularly pointed out 100 in the claims hereto appended.

Referring to the drawings,

Fig. 1 is a view, from the shaft side, of a dumbwaiter unit embodying my invention;

Fig. 2 is a vertical section on the line 2—2 105 of Fig. 1;

Fig. 3 is a horizontal section on the line 3—3 of Fig. 1 upon an enlarged scale; and

Fig. 4 is a plan view of one upper corner of the upper door section.

Like letters refer to like parts throughout the several views.

5 In the embodiment of the invention shown in the drawings, I employ a sheet metal form defining a door opening in a shaft, the bottom rail *a* of this form constituting the sill, the top rail *b*, the lintel, and the side rails *c* and *d*, the jambs, of the opening. At the front and the back of the various rails *a*, *b*, *c* and *d* are outwardly extending flanges *a'*—*a*², *b'*—*b*², *c'*—*c*² and *d'*—*d*², respectively, so spaced with relation to each other as to 10 form pockets of substantially the width of the thickness of the wall of the shaft, and adapted to receive the masonry of the wall. Due allowance should be made for the plaster finish upon the room side of the shaft. 15 20 With this construction of frame or form, the mason may run his courses to the height of the sill of the shaft opening, and then place the form upon the top course, and by leveling up the sill bring the side frames plumb with 25 the wall. When the form is so positioned, and the rear flange *a'* brought tightly against the shaft side of the upper course of the wall completed to that point, the mason may 30 build up the wall about this frame, the bricks being brought close to the side rails, and the lintel rail forming an arch supporting the course above the form.

Since the spaced flanges have no obstructions between same, no extraordinary care is 35 required in laying the bricks, and the frame, in its entirety, may be firmly imbedded in the masonry.

Secured to the flanges *c'* and *d'* are vertically extending guides *e* and *f*, projecting 40 above and below the rails *b* and *a* respectively for a distance sufficient to permit the desired opening movement of the door panels in a manner to be hereinafter referred to. The guides *e* and *f* may be secured to the 45 flanges of the form in any desired manner, but preferably they are welded thereto, either continuously or at spaced distances, so as to ensure adequate support therefor from the flanges *c'* and *d'*.

50 The rails *e* and *f* are preferably made of sheet metal, channelled as shown, with one of the side flanges, that secured to the rails *c'* and *d'*, wider than the other flange in order to facilitate the attachment of the 55 guides or rails to said rails. The wide flanges are indicated at *e'* and *f'*, and the narrow flanges at *e*² and *f*². The channels of the guides or rails are open at both the top and the bottom.

60 It will be noted that by this construction, the guides or rails, in their entirety, are positioned within the shaft. If desired, the portions of the guides or rails *e* and *f* above the lintel rail may be connected by a reenforcing cross bar *g* to stiffen this portion of

the rail structure. In view of the fact, however, that the doors are very light in their construction, and the channelled guide rails possess considerable inherent rigidity, notwithstanding that they may be made of light sheet metal stock, reinforcement of this kind may be dispensed with, if desired. 70

Toward the top of the guides or rails, they are cut away, except as to the wide flanges *e'* and *f'*, for a distance sufficient to admit 75 of the mounting thereon of small sheaves *h* and *i*.

Slidably mounted in the guides or rails *e* and *f* are two sheet metal door panels *j* and *k*, which panels are connected by means of rods and chains, tapes *m* and *n*, or any other desired flexible means passing over the sheaves *h* and *i*. The upper panel *j* is provided with a top flange *j'* and side flanges *j*² and *j*³, and an astragal *j*⁴ formed integrally 80 with the metal of the channel and offset so as to be presented upon a plane inwardly of the plane of the face of the panel toward the floor side of the shaft. The top flange is slotted as at *j*⁵ to afford means for connections of the flexible means *m* and *n* with the panel *j*. The opposite ends of the flange *j'* are also cut away as at *j*⁶ to afford clearance for the run of said connections *m* and *n* past the panel *j* into engaging relation with the 85 panel *k*. There is no flange at the bottom of this panel *j*.

The lower panel *k* is similarly flanged at all edges thereof, the flanges being indicated at *k'*, *k*², *k*³ and *k*⁴. The opposite corners of the flange *k'* are cut away as shown, to afford clearance for the passage of the connections *m* and *n* to an attaching device carried by the panel. Other means of attaching the 90 connections may be employed, if desired, but preferably I use fittings such as are shown in the drawings, since these may also be utilized as bearing shoes affording isolated areas of small dimensions co-operating with the walls of the channels of the guides *e* 95 and *f*.

Ordinarily the connections *m* and *n* between the two panels *j* and *k* comprise a sprocket chain section co-operating with the sheaves *h* and *i* and the panel *j*, and rods connected with said chains and co-operating 100 with the panel *k*, the lower end of these rods being screw threaded.

Secured to each upper corner of the panel *k* is a malleable iron fitting *o* having a 105 pierced lug *o'*, through which said rods may pass and are secured in adjustable relation by means of nuts *o*². The top flange *k'* of the panel *k* is preferably cut away to accommodate the fitting *o*, and the body of said 110 panel and the flange *k*² or *k*³ thereof is pierced to permit bearing projections *p* and *p'* upon said fitting *o* to pass beyond the 115 panel into engaging relation with the walls of the guide or rail *e* or *f*. A third bearing 120

125 130

projection p^2 passes beyond the edge of the flange h^2 or h^3 into engagement with the narrow flange e^2 or f^2 of the guide rail. Similar fittings q having projections q' , q^2 and q^3 extending beyond the panel h in the manner above described, are used at the bottom corners of this panel.

The upper panel j at each corner thereof is provided with fittings q having projections q' , q^2 and q^3 passing through openings 10 in the panel and the side flanges thereof into co-operating relation with the guide or rail structures $e-f$ in the manner above referred to in connection with the fittings o . The fittings q at the upper corners of the section j , partially close the cut away portion j^6 of the flange j^1 .

The various fittings o and q may be secured to the panel in any desired manner, 20 preferably by means of spot welding methods. These fittings may be of light-weight castings, since they are required to sustain but very little load by reason of the light construction of the panels in their entirety. 25 Their use, however, will serve to give a fairly close sliding fit between each panel and the rails or guides in which they have movement, and affords very small contact areas admitting of ease of movement of the 30 panels with a minimum of wear.

The main advantages of a dumbwaiter door structure embodying my invention are that it is fairly light in weight, may be assembled in its entirety as a single unit in 35 the factory, and by reason of the construction of the form or frame, may be quickly placed in position during the erection of the wall of the shaft, and when in position will materially assist in the construction of this 40 wall rather than introduce difficulties in the way of the mason. Its light weight permits it to be handled with great ease by two men, and the flanged construction of the rail a when it is once positioned upon the wall, 45 will ensure its remaining in position, and in the proper position, without any attention excepting the necessary leveling up to make the side rails thereof plumb. No bracing of any kind is required.

The front flanges a^2 , b^2 , c^2 and d^2 may be 50 pressed into any desired decorative form as shown in the drawings, this flange constituting the trim about the floor side of the dumbwaiter opening. While, when such trim is used, allowance must be made for the 55 finishing plaster coats, it is obvious that the lower end of the rail structures e and f will prevent any toppling of the unit inwardly of the shaft while the masonry is being 60 built up about the frame or form, and that the space within the molded portion of said flanges may be filled with mortar or cement during the construction of the wall. In fact, even when a molded flange is used, a portion 65 of this flange will be spaced from the

opposite flange as to engage the wall of the shaft and thus hold the whole structure firmly in position in relation to this wall.

The panel j is provided with any desired form of operating handle as r , and the construction is such that any desired form of lock may be applied to the panels. Since this detail is immaterial to, and forms no part of, the present invention, no showing of a lock is made in the drawings.

It will be noted that the door, as to its various parts, is so designed that no work thereon is required when installing. While the frame or form and the guides in a completed door are a unitary structure, these 70 parts may be manufactured separately and assembled by welding or other methods. While the molding flange is practically an integral part of the frame or form, it ordinarily is made up of separate units welded 75 together, and welded to other portions of the frame or form. It is to be noted that the frame or form has no flanges excepting those which are adapted to lap the opposite sides 80 of the wall. Cross flanges are unnecessary 85 and undesirable.

Various parts entering into the construction of the door, including the panels, but excepting the various fittings when used, the sheaves and the connections between the 90 panels are all of sheet metal, drawn, bent or rolled to form. I have gotten very excellent results when using 14 gauge sheet iron. The flanges a' , b' , c' and d' may be made by a bending operation, and the corners left open, 100 since these flanges are within the shaft where appearance is no factor. The molded flanges a^2 , b^2 , c^2 and d^2 , however, afford a continuous decorative trim about the opening, their mode of construction being such 105 as to prevent open corners.

It is not my intention to limit the invention to the precise details of construction shown in the drawings, since it is apparent that there may be wide variance in such details without departing from the spirit and scope of the invention.

Having described the invention, what I claim as new and desire to have protected by Letters Patent, is:—

1. A dumbwaiter door embodying therein a sheet metal form composed of a bottom, a top and parallel spaced side rails permanently connected and, defining the door opening in a shaft, said rack respectively forming the sill, the lintel and the jambs of said opening, and having outwardly extending flanges so spaced as to receive the masonry of the shaft about the opening within said form, guides carried by flanges of the side rails of said form and extending vertically beyond said top and said bottom rails respectively, sheet metal door panels slidably mounted in said guides, sheaves carried by said guides, and flexible connections extend- 115 120 125 130

ing from one of said panels to the other, and passing about said sheaves.

2. A dumbwaiter door embodying therein a sheet metal form composed of a bottom, a

5 top and parallel spaced side rails permanently connected and, defining the door opening in a shaft, said rails respectively forming the sill, the lintel and the jambs of said opening, and having outwardly extending 10 flanges so spaced as to receive the masonry of the shaft about the opening within said form, channelled guides formed of sheet metal carried by flanges of the side rails of said form and extending vertically beyond 15 said top and said bottom rails respectively, sheet metal door panels slidably mounted in the channelled portion of said guides, sheaves carried by said guides, and flexible connections extending from one of said panels to the other, and passing about said 20 sheaves.

3. A dumbwaiter door embodying therein a sheet metal form composed of a bottom, a top and parallel spaced side rails permanently connected and, defining the door opening in a shaft, said rails respectively forming the sill, the lintel and the jambs of said opening, and having outwardly extending flanges so spaced as to receive the masonry 25 of the shaft about the opening within said form, guides carried by flanges of the side rails of said form and extending vertically beyond said top and said bottom rails respectively, sheet metal door panels slidably 30 mounted in said guides, one of said panels having flanges at the top and at the sides thereof, and an astragal at the bottom thereof, said flanges and said astragal being an integral part of the metal of said panel, and the other of said panels having integral 35 flanges at all edges thereof, sheaves carried by said guides, and flexible connections extending from one of said panels to the other, and passing about said sheaves.

4. A dumbwaiter door embodying therein a sheet metal form composed of a bottom, a top and parallel spaced side rails permanently connected and, defining the door opening in a shaft, said rails respectively forming the sill, the lintel and the jambs of said opening, and having outwardly extending flanges so spaced as to receive the masonry 40 of the shaft about the opening within said form, channelled guides formed of sheet metal carried by flanges of the side rails of said form and extending vertically beyond said top and said bottom rails respectively, sheet metal door panels slidably mounted in the channelled portion of said guides, one 45 of said panels having flanges at the top and at the sides thereof, and an astragal at the bottom thereof, said flanges and said astragal being an integral part of the metal of said panel, and the other of said panels having integral flanges at all edges thereof, cast metal fittings, each 50 having a pierced lug toward the top of the lower panel, sheaves carried adjacent the tops of said guides, flexible connections, the opposite ends of which are secured to the 55 upper panel by means of said slots, and to

sheaves carried by said guides, and flexible connections extending from one of said panels to the other, and passing about said sheaves.

5. A dumbwaiter door embodying therein a sheet metal form composed of a bottom, a top and parallel spaced side rails permanently connected and, defining the door opening in a shaft, said rails respectively forming the sill, the lintel and the jambs of said opening, and having outwardly extending flanges so spaced as to receive the masonry of the shaft about the opening within said form, guides carried by flanges of the side rails of said form and extending vertically beyond said top and said bottom rails respectively, sheet metal door panels slidably mounted in said guides, sheaves carried by said guides, a flange having slots therein at the top of the upper panel, cast metal fittings each having a pierced lug at the top of the lower panel, and flexible connections, the opposite ends of which are secured to the upper panel by means of said slots, and to the lower panel by means of said lugs, said 85 connections passing about said sheaves.

6. In a dumbwaiter door, a panel having flanges at the opposite sides thereof, and cast metal fittings within the flange of said panel, and having projections thereon extending through and beyond the face of the panel, beyond the edge of said flange, and through and beyond said flange, whereby each of said fittings presents three bearing points of limited area adapted to co-operate 100 with a guide rail structure in which said panel is slidably mounted.

7. A dumbwaiter door embodying therein a sheet metal form composed of a bottom, a top and parallel spaced side rails permanently connected and, defining the door opening in a shaft, said rails respectively forming the sill, the lintel and the jambs of said opening, and having outwardly extending flanges so spaced as to receive the masonry 105 of the shaft about the opening within said form, channelled guides formed of sheet metal carried by flanges of the side rails of said form and extending vertically beyond said top and said bottom rails respectively, sheet metal door panels slidably mounted in the channelled portion of said guides, the upper of said panels having a flange at the top thereof, having slots adjacent the opposite sides thereof, flanges at the sides thereof, and an astragal at the bottom thereof, said flanges and said astragal being an integral part of the metal of said panel, and the lower of said panels having integral flanges 110 at all edges thereof, cast metal fittings, each having a pierced lug toward the top of the lower panel, sheaves carried adjacent the tops of said guides, flexible connections, the opposite ends of which are secured to the upper panel by means of said slots, and to 115

the lower panel by means of said lugs, said connections passing about said sheaves, and other cast metal fittings within the flange of said lower panel and the side flanges of said upper panel, each of said metal fittings having projections thereon extending through and beyond the face of the panel, beyond the edge of said flange, and through and beyond

said flange, whereby each of said fittings presents three bearing points of limited area ¹⁰ adapted to co-operate with a guide rail structure in which said panel is slidably mounted.

In witness whereof I have hereunto affixed my signature, this 31st day of March, 1927.

PAUL R. SAURER.
